Attorneys.

UNITED STATES PATENT OFFICE.

MANUEL D. DOMINGUEZ, OF NEW ORLEANS, LOUISIANA, ASSIGNOR OF ONE-HALF TO CHARLES A. DENIS AND ONE-HALF TO GEORGE SARPY, BOTH OF NEW ORLEANS, LOUISIANA.

TELEPHONE DIAPHRAGM.

Application filed March 19, 1924. Serial No. 700,247.

To all whom it may concern:

Be it known that I, MANUEL D. DOMINGUEZ, a citizen of Spain, and resident of New Orleans, in the parish of Orleans and State of Louisiana, have invented certain new and useful Improvements in Telephone Diaphragms, of which the following is a specification.

My invention relates to acoustic diaphragms of types especially adapted for use in telephone receivers.

An important object of the invention is to avoid objections to operative characteristics of magnetic or metallic diaphragms, including sound distortion and other defects incident to the use of such diaphragms, as is well understood by persons skilled in the art.

I substitute for the ordinary diaphragm of magnetic metal a non-magnetic and preferably a non-metallic diaphragm which is not subject to the distortion effects of the ordinary metal or magnetic diaphragm, and is capable of reproducing various sounds, including articulate speech, with practically complete fidelity.

Various materials may be employed for the main diaphragm, including mica, celluloid, certain kinds or grades of paper, organic membranes, hard rubber, and others enumerated in the detailed description. A magnetic element such as a small disc of thin soft iron is attached to the main diaphragm, usually at the center thereof, to move the diaphragm by variations in the magnetic flux of the receiver magnets.

The characteristics and advantages of the invention are further sufficiently explained in connection with the following detail description of the accompanying drawing, which shows various structures embodying the invention. After considering these examples, skilled persons will understand that many variations may be made within the principles of the invention, and I contemplate the employment of any structures that are properly within the scope of the appended claim.

Fig. 1 is a view, partly in elevation and partly in section, of one typical telephone receiver, with a diaphragm constructed in accordance with my invention incorporated therein.

Fig. 2 is a front elevation of the same with cap or cover removed.

Fig. 3 shows a modified form of dia- 55 phragm in elevation and section.

Figs. 4, 5 and 6, show in a similar way other modified diaphragm structures.

In Figs. 1 and 2, 1 is any suitable case or housing for a telephone receiver, including 60 the electromagnets 30, and provided with the ordinary centrally-apertured removable cap or cover 31, which is arranged to clamp the diaphragm against the wall of the case, as usual.

The diaphragm 2 is of any suitable non-magnetic, and preferably non-metallic material, such as mica, celluloid, stiff paper, organic membrane, hard carbon or graphite, hard rubber, thin glass, certain kinds of 70 wood, ivory, or other material.

The diaphragm is clamped about its margin in the usual way and acts merely as an acoustic element to impart vibrations to the air by its oscillation, and it does not act as usual as an electro-magnetic element, and is therefore free from the disadvantageous properties of such materials. To impart vibrations to the diaphragm by reason of variations in the magnetic field, a suitable mag- 80

netic element such as the disc 4 is provided, which is connected to the diaphragm at the center, by means of a screw 3, nut 6 and spacing washers 5. The magnets and the main diaphragm are so located that the 85 magnetic disc 4, which is usually of soft iron, is spaced properly away from the magnet poles. In this arrangement the magnetic disc has no acoustic properties, but serves merely as an operating member for the dia- 90 phragm, and it may therefore be referred to in some cases as an "armature" operated by the magnets and connected to the diaphragm.

In Fig. 3 the diaphragm 8 may consist specifically of mica, and the operating ele- 95 ments or armatures 8' and 9 are thin discs of soft iron, usually much smaller than the diaphragm and secured to it by a suitable adhesive.

In Fig. 4 the thin iron operating element 100 or armature 10 is secured directly to the dia- phragm 11 by a screw 12 and nut 14, with or without an interposed washer 13.

In Fig. 5 the diaphragm 15 of non-magnetic material may be in the form of an annulus, and the central space may be filled with soft iron filings 18 confined between thin metal discs, 16, or in some cases, the discs

which confine iron filings may be of non-magnetic material such as mica or other suitable material similar to that of the diaphragm, and secured adhesively. In this case the iron filings act as the magnetic element or armature.

Fig. 6 shows that the operating element or armature disc may be of other than circular shape. Specifically, in this instance, it is square, and is glued or otherwise secured to the diaphragm 20, which may be of any of the materials above stated or other similar or equivalent materials.

When necessary or desirable, a rubber packing ring may be interposed between the mica diaphragm and receiver case 1 or be-

tween the diaphragm and the cap 31, or both. This arrangement has been employed in connection with metallic diaphragms and is therefore not particularly illustrated.

20

I claim:

A diagram structure for telephones and like uses, comprising a non-magnetic diaphragm, plates secured at opposite faces of the diaphragm in spaced relation, and comminuted magnetic metal substantially filling the chamber provided by the plates.

25

Signed at New Orleans, in the parish of Orleans and State of Louisiana this 28th day of February A. D. 1924.

MANUEL D. DOMINGUEZ.
